[57] CLAIM

The ornamental design of a foldable fishing lure holder,
as shown and described.

DESCRIPTION

FIG. 1 is a perspective view of a foldable fishing lure
holder showing my new design;

FIG. 2 is an end elevational view, the opposite end
being a mirror image thereof;

FIG. 3 is a bottom plan view;

FIG. 4 is a top plan view thereof;

FIG. 5 is a perspective view of a foldable fishing lure
holder in a closed, folded position.

The broken line representation of fishing lures in FIGS.
1, 2 and 4 are for purposes of illustration only and form
no part of the claimed design.

FIG. 3.

FIG. 4.

FIG. 5.
